Attorney.

UNITED STATES PATENT OFFICE.

FRANK ANSTETT, OF WILKES-BARRE, PENNSYLVANIA.

SAXOPHONE.

Application filed November 21, 1921. Serial No. 516,602.

To all whom it may concern:

Be it known that I, FRANK ANSTETT, a citizen of the United States, residing at Wilkes-Barre, in the county of Luzerne and State of Pennsylvania, have invented certain new and useful Improvements in Saxophones, of which the following is a specification.

This invention relates to saxophones, and more particularly to tenor saxophones in B flat; and it consists in certain improvements to the key mechanism for producing the tones of C natural, and the upper tones D, E flat, E, and F, as hereinafter fully described and claimed.

In the drawings, Figure 1 is a side view of the upper end portion of a tenor saxophone constructed according to this invention, with the mouthpiece and various parts omitted. Fig. 2 is a side view looking in the direction of the arrow 6 in Fig. 1. Fig. 3 is a similar view but looking in the direction of the arrow 7 in Fig. 1. Fig. 4 is a cross-section, taken on the line 4-4 in Fig. 3.

The saxophone illustrated is a tenor saxophone in B flat of approved construction, provided with a conical body portion 8, and a curved head joint 9 having a cork packing piece 10 to receive the usual mouthpiece. The body portion is provided with the usual button or thumb rest 12 for the thumb of the left hand, and 14 is the key which controls the vent pad 15, of the upper octave, on the head joint. In a saxophone as ordinarily constructed, the ball of the thumb of the left hand rests directly on the button 12, and the thumb piece 13 of the octave key 14 is operated by the tip of the thumb without raising the ball of the thumb off the button. According to the present invention, the ball of the thumb does not rest directly on the button 12 but on a thumb plate 32 which is normally pressed down on the button 12 by the thumb, and which permits the octave key 14 to be operated by the tip of the thumb in the usual manner. The vent pad 16 of the lower octave is preferably controlled by automatic mechanism of approved construction, and 17 is the arm which operatively connects it with the key 14.

The first, second and third fingers of the left hand come over finger plates 18, 19 and 20, respectively. These finger plates pertain to the normal C, A and G pads of the

approved instrument as ordinarily constructed. The finger plates 18 and 19 and the keys to which they pertain are mounted co-axially, and independently of each other, 60 on one spindle as shown in Fig. 2; and the finger plate 20 is mounted on a separate spindle.

The pad 21 which closes the C sharp hole, and which produces that tone when raised, 65 is closed by crossfingering with the second finger on the plate 19, in order to produce the tone of C natural. This action leaves the C pad 24 open. In running up the scale of D major the notes A natural, B 70 natural and C sharp are produced one after another by raising the third, second and first fingers of the left hand off the finger plates 20, 19 and 18, in the regular order of third, second and first. The C natural 75 is produced by depressing the finger plate 19 with the second finger simultaneously with raising the first finger, and so that the sound of one note only may be heard. In running up the scale of C major the 80 third and second fingers are raised in the order third and second, and then the second finger is moved downwardly, crosswise of the first finger, while the first finger is being raised. This is not so easily done in rapid 85 passages on account of the cross motion of the fingers. A C pad 25 is also provided at the back part of the instrument body for forming the C natural tone by a different fingering. This pad 25 is operated in the 90 usual manner by a pivoted key 26 which is normally closed by a spring 27, and which is tripped open by an arm 28 on a key operated by the first finger of the right hand, at the lower part of the instrument, and 95 which is not shown as it and also the key 26 and pad 25 are of ordinary approved construction.

In order to avoid making the C natural by crossfingering with the second finger of 100 the left hand on the plate 19, and by the use of the key 26, and thereby to facilitate the execution of certain passages of music, an additional key 30 is provided. This key 30 is mounted on a pivot 31, and it has a thumb 105 plate 32 at its upper end arranged over the button or thumb rest 12. This key 30 has a laterally and forwardly projecting arm 33 which underlays a projection 34 on the upper end of the C pad 25. The key 30 110 is provided with a strong spring 35 which overcomes the spring 27 and opens the C

pad 25 when the plate 32 is relieved from the pressure of the thumb. The thumb piece 13 of the octave key 14 is arranged so that it can be operated by the thumb in the usual manner, but the thumb is in contact with the thumb plate 32 instead of being on the button, and the button forms a stop for the plate 32 to bear against.

The highest tones of the instrument, F, E, 10 E flat, and D, are produced by pads 36, 37, 38, and 39, respectively, which cover the respective tone holes, and which produce the tones when raised to open the tone holes, in the usual manner. The D tone in instruments as ordinarily constructed, is produced by a key operated by the third joint of the 15 first finger of the left hand. According to the present invention, the D key 40, which is mounted on a pivot 41, is extended longitudinally, and it has a curved and laterally projecting finger piece 42 which extends forwardly around the tube or body portion of the instrument to a point between the finger plates 19 and 20. In this position the D 20 key is opened with facility by the third finger of the left hand, which is raised off the plate 20.

The E flat tone is ordinarily produced by a key operated by the first finger of the 30 left hand. According to the present invention, the E flat key 44, which is mounted on a pivot 45, is extended longitudinally, and it has a laterally and forwardly projecting finger piece 46 at its lower end which extends to a point between the finger plates 18 and 19. This finger piece 46 is depressed by the second finger of the hand, which is removed from the plate 19, so that the pad 38 may be raised by the key 44 to produce 35 the E flat tone.

The high E natural tone is produced by the first finger of the left hand according to this invention, applied to a finger piece 48 carried by the E lever 49 which is mounted on a pivot 50.

The upper end portion of the lever 49 underlays an arm 51 on the E pad 37, and when the finger piece 48 is depressed, the pad 37 is raised to produce the E natural 50 tone. This tone is also produced in the usual manner by the first finger of the right hand at the lower part of the instrument, which also operates the E natural pad 37. The finger piece 48 is arranged on a level with the finger plate 18, and the lower end portion 55 of the E key is arranged to overlap the finger piece 46 of the E flat key, so that the E flat pad is raised each time the E natural pad is raised, in order to increase the ventage and improve the quality of the E natural tone.

The high F tone is also produced by the first finger of the left hand. The high F key 54 is mounted on a pivot 55, and it has 60 a laterally and forwardly projecting finger

piece 56 on its lower end portion, which projects crosswise of and under the lower end portion of the E natural lever 49. The finger piece 56 is arranged on the other side of the finger plate 18 from the finger plate 19, and the first finger is removed from the plate 18 in order to depress the finger piece 56 and thereby raise the F pad 36.

This arrangement of the high D, E flat, 75 E, and F keys facilitates the execution of certain passages of music, in which these keys are used. The three finger pieces 56, 46 and 42 are arranged substantially parallel to each other, and they alternate in regular order with the finger plates 20, 19 80 and 18, the series being, 20, 42, 19, 46, 18 and 56, and each finger piece projects at substantially a right angle from the key to which it pertains.

This arrangement of finger pieces and 85 finger plates permits the four upper tones of the instrument to be produced without moving the left hand to an inconvenient extent from its normal position on the instrument. 90

What I claim is:

1. In a saxophone a C natural key provided with a closing spring, a key pivoted adjacent to the said C key and provided with means for engaging with it and having a plate for the thumb of the left hand, and a spring of greater strength than the aforesaid spring and which operates both keys when the thumb plate is released and thereby opens the said C key to produce the 100 C natural tone.

2. In a saxophone, a normally closed C natural key provided with a closing spring and having a projection at its upper end, a key pivoted adjacent to the said C key and provided at its upper end with a plate for the thumb of the left hand and a laterally projecting arm which underlays the projection on the said C key, and a spring of greater strength than the aforesaid spring 110 and which operates both keys when the thumb plate is released and thereby opens the said C key to produce the C natural tone.

3. In a saxophone, a body portion provided with a button, a normally closed C 115 natural key provided with a closing spring, a key pivoted adjacent to the said C key and provided with means for engaging with it and having a plate for the thumb of the left hand which overlaps the said button and which bears on it when depressed, and a spring of greater strength than the aforesaid spring and which operates both keys when the thumb plate is released. 120

4. In a saxophone, a pivoted key provided 125 with a pad for the high E flat tone at its upper part and having a lateral projection at its lower part, and a pivoted lever for operating the high E natural pad, said lever being arranged to overlap the said projec- 130

tion and raise the E flat pad simultaneously with the E natural pad.

5. In a saxophone, a pivoted key provided with a pad for the high E flat tone, said key having a laterally and forwardly projecting finger piece at its lower end adapted to be operated by the second finger of the left hand to raise the E flat pad, and a pivoted lever for operating the high E

10 natural pad, said lever having a finger piece

at its lower end portion adapted to be operated by the second finger of the left hand, and having an end portion which overlaps and engages with the finger piece of the E flat key so that the E flat pad is raised simultaneously with the E natural pad. 15

In testimony whereof I have affixed my signature.

FRANK ANSTETT.
